UNITED STATES PATENT OFFICE.

MORRIS D. ARNOW, OF BOSTON, MASSACHUSETTS.

CLASP.

No. 880,116.

Specification of Letters Patent.

Patented Feb. 25, 1908.

Application filed February 21, 1907. Serial No. 358,644.

To all whom it may concern:

Be it known that I, MORRIS D. ARNOW, of Boston, in the county of Suffolk and State of Massachusetts, have invented certain new and useful Improvements in Clasps, of which the following is a specification.

This invention relates to a fastening device for boots, shoes, over-shoes, gaiters, gloves and the like, which may be generally em-
10 braced under the term "foot and hand cover-
ings," and has for its object to enable such articles of wear to be quickly fastened, and to be readily adjusted so as exactly to fit the wearer in all parts. Accordingly I form the
15 clasp with interengaging members, one of which has a series of teeth with which the other engages, and arranged so that they may be connected in a wide range of different positions so as exactly to fit the hand or foot
20 of the wearer, and to take up looseness due to stretching after long use.

Of the accompanying drawings,—Figure 1 represents a perspective view of the upper part of a shoe having my improved clasp applied thereto. Fig. 2 represents a fragmentary front elevation of part of the shoe, with one of my clasps thereon. Fig. 3 represents a fragmentary section, showing the manner of securing one of the members of the
25 clasp. Figs. 4 and 5 represent plan and sec-
tional views of the clasp as applied to a shoe.
Figs. 6 and 7 represent perspective views of the members of the clasp when separated
30 from each other. Fig. 8 represents an end view of the socket member of the clasp. Fig.
35 9 represents a plan of the blank from which the socket member is formed. Fig. 10 represents the device as applied to a glove. Figs. 11 and 12 represent different arrangements
40 for attaching the clasp to a shoe. Fig. 13 represents a sectional view of the socket member showing a modification in construc-
tion.

The same reference characters indicate the
45 same parts in all the figures.

The clasp or fastening consists of a socket member *a* having bottom, side and top walls and open at one end to receive a tongue member *b*. In the upper or outer wall of the socket
50 member are locking shoulders or teeth *c*, preferably made integral by corrugating the blank from which the socket is formed, and these shoulders or teeth are arranged for engagement with an integral spring latch *d* on the tongue member. The latter is made of sheet metal and between the ends is cut so as

to separate three sides of the latch *d*, leaving the fourth side connected. The latch is bent up so as to lie oblique to the tongue member and to slant outward and rearward from the front end thereof. Thus when the tongue member is inserted into the socket, the latch is depressed by the locking shoulders but springs up behind them and locks the tongue so that it cannot be withdrawn by a pull alone.

In the outer face of the socket is a longitudinal slot *e* through which project a knob or projection *f* on the latch *d*, and a pin *g* on the forward end of the tongue member. The projection *f* serves to depress the latch out of engagement with the teeth so that the tongue can be withdrawn, while the pin *g* is provided for drawing the tongue inward into the socket.

As shown in Fig. 9, the socket member is made from a flat blank *h* of sheet metal. At each end of the blank are left one or more prongs *i* which are pointed so as to be inserted through the material of the part to which they are fastened, and the opposite sides are corrugated by pressure so as to make the teeth *c*. The sides are then bent upward on the dotted lines *j*, and inward toward each other on the lines *k*. Adjacent the rear end of the socket the side edges *l* extend outwardly sufficiently far to butt together when the socket is shaped, but the edges outside of the teeth are slightly cut out so as to leave the slot *e*. At the rear end of the blank are one or more tongues *m* which bend inward between the inner and outer walls so as to close the end of the socket as shown in Figs. 6 and 8. The prongs *i* are bent downward into parallelism and inserted through the material of the hand or foot covering, being then bent back and clenched, as shown in Fig. 5, to secure the socket.

The tongue member has an extension *n* on the sides of which are lips or flanges *o* which are adapted to be closed down on short strap members or lugs *p* on the articles to which they are attached. These lips or flanges are pressed down tightly and may be acted upon by a machine which cuts and forces spurs from the metal into the leather of the shoe, etc., at the same time that the lips are being clamped. Preferably the body of the tongue *b* and the extension *n* are made in separate parts, although they may also be integral, and are pivotally connected by a projection *q* on the part *n* which passes through a slot *r*

in the rear of the tongue body, and is doubled back over the edge thereof. This makes a sort of pivotal connection, giving flexibility to the tongue member. The tongue members are attached to lugs *p* as before described, and these latter may be formed integrally with the upper of the shoe by cutting away the latter adjacent the edge, as shown in Figs. 1, 2, 3 and 11, or the lugs may be formed upon a strip *s* separately sewed to the outside of the upper adjacent and parallel with the edge thereof. In applying the fastening to gloves, one or more tabs *t* of leather are sewed at one end to the glove, and the other end is clamped by the lips *o* of the tongue member, as described.

It will be understood that Figs. 4 to 9 inclusive show the clasp on a greatly enlarged scale, for the purpose of clear illustration.

Actually the device will be made of approximately the same size as the illustration in Fig. 1. The length of the parts will be varied according to the use for which it is designed, and the number of teeth and spacing between them will be likewise varied. In any event, there will be a wide range of positions in which the members of the clasp may be secured. Thereby a foot or hand covering of a particular size is adapted to be secured about ankles or wrists of greatly varying circumference, and in the case of a foot covering, the several parts may be drawn together with exactly the right tension to fit comfortably about different parts of the ankle. When the leather or other material becomes stretched after use, the tongue may be pushed inward by the space of a few teeth so as to take up the slack and maintain a snug fit.

It is to be understood that the locking shoulders or teeth are not necessarily made by forming integral offsets, but that they may be equally well formed by cutting out tongues or spurs, and forcing them inward a slight distance below the upper surface of the socket. Such a form is shown at Fig. 13.

I claim:—

1. A clasp for foot and hand coverings, consisting of socket and tongue members fastened respectively to adjacent separable parts of the covering, the socket member being open at one end to receive the end of the tongue member and having internal teeth, and the tongue member having an integral resili-

ent latch inclined away from the free end of the tongue, adapted to slip over the teeth when the tongue is pushed into the socket and to engage behind the teeth. 55

2. A clasp consisting of a socket member having a plurality of spaced shoulders inclined inwardly toward the interior of the said member, and a tongue member adapted to enter said socket member and carrying an outwardly inclined integral spring latch to slip past the shoulders when inserted into the 60 socket and to engage behind the shoulders and prevent withdrawal of the tongue. 65

3. A clasp consisting of a socket member having internally projecting locking shoulders or teeth and a slot, a sheet-metal tongue provided with an integrally united latch struck up from the metal thereof between its ends, whereby said latch may be entirely retracted within the body of the tongue, adapted to enter the socket and interlock with the shoulders, and a projection on the tongue extending through the slot of the socket when the members are together, to be engaged manually for drawing the tongue a further distance into the socket. 70

4. A clasp for securing separable parts of foot or hand coverings comprising a socket member having locking teeth and prongs for attachment to one of the parts, and a tongue member having lips or flanges to be clamped 75 about a lug on the other part, said tongue member being adapted to enter the socket member and carrying a spring latch for automatic engagement with the teeth thereof as the tongue member is inserted into the socket. 80

5. A clasp comprising socket and tongue members adapted to be engaged telescopically, the former having a plurality of locking shoulders or teeth and the latter a spring latch to engage behind said teeth, and a fastening device for the tongue member having a projection passed through a slot in the tongue member and doubled back for pivotal union therewith, and having flanges or lips adapted to be clamped about a portion of the article 95 to which it is applied. 100

In testimony whereof I have affixed my signature in presence of two witnesses.

MORRIS D. ARNOW.
